EMIL BRECHT AND RUDOLF FUGMANN, OF GUBEN, GERMANY.

BLOWING MACHINE FOR THE MANUFACTURE OF HATS.

Application filed March 4, 1927, Serial No. 172,809, and in Germany March 12, 1926.

This invention relates to a blowing machine for the manufacture of hats, particularly what are known in the trade as hat hoods.

- 8 In blowing machines hitherto used, only one cone is employed in the blowing compartment. When it is desired to make hat hoods of different sizes, it is therefore necessary either to keep in readiness blowing machines suited for the different sizes or to insert into a machine suitable for the largest hoods, a correspondingly smaller cone for the manufacture of smaller hoods, so that the machine is not completely utilized.
- 10 15 It has been found that small hoods can be manufactured also with machines of the larger dimensions, in such a manner that several smaller cones, for instance, three, are accommodated in a single blowing compartment. It has also been found unexpectedly that during the matting or forming, the filaments or fibres introduced became uniformly distributed among the cones which of course are preferably mounted in a symmetrical 20 25 manner.

In this way the necessity of keeping ready machines of different sizes for the different sizes of hoods is avoided. The output is substantially increased as compared with that of machines in which the large cone is replaced by a single smaller cone, so that an increase in the number of machines is unnecessary.

Part of a blowing machine embodying the invention is diagrammatically illustrated by way of example in the accompanying drawing, in which:

Figure 1 is a vertical section and

Figure 2 a plan, both partly in section.

40 45 1 is the usual blowing compartment, the bottom 2 of which is rotatable in the well known manner. In place of the usual single cone rotating with the bottom, in the construction illustrated there are provided three smaller cones 3 which are supported by a perforated plate 4. This plate rests on the rotating bottom 2 of the compartment and rotates with the same. It may be secured to the bottom 2 in any suitable manner. The

openings 5 situated under the cones, may be surrounded by a raised edge or flange 6 which holds the cones 3 fast. It is not essential that the individual cones should be capable of rotating about their axes, as even without this rotation, the fibres introduced into the compartment in the usual manner, become uniformly distributed among the several cones and settle on them.

What we claim is:

1. In a blowing machine for the manufacture of hat hoods the combination, with the blowing compartment, of a plurality of perforated forming cones adapted to receive the deposit of fibrous material introduced into the compartment, said cones being supported by and rotating with the bottom of the compartment.

2. In a blowing machine for the manufacture of hat hoods the combination, with the blowing compartment, of a plurality of perforated forming cones adapted to receive the deposit of fibrous material introduced into the compartment, said cones being supported by a perforated plate resting on and rotating with the bottom of the compartment.

3. In a blowing machine for the manufacture of hat hoods the combination with the blowing compartment, of a plurality of symmetrically arranged perforated forming cones adapted to receive the deposit of fibrous material introduced into the compartment, said cones being supported by and rotating with the bottom of the compartment.

4. In a blowing machine for the manufacture of hat hoods, the combination, with the blowing compartment, of a plurality of symmetrically arranged perforated forming cones adapted to receive the deposit of fibrous material introduced into the compartment, said cones being supported by a perforated plate resting on and rotating with the bottom of the compartment.

In testimony whereof we have affixed our signatures.

EMIL BRECHT.
RUDOLF FUGMANN.
